P. MERTES, JR

ATTACHMENT FOR RADIO RECEIVING SETS

Filed Feb. 5, 1927

INVENTOR:
Peter Mertes, Jr.
BY David E. Carlsen.
ATTORNEY.

UNITED STATES PATENT OFFICE.

PETER MERTES, JR., OF ST. PAUL, MINNESOTA.

ATTACHMENT FOR RADIO RECEIVING SETS.

Application filed February 5, 1927. Serial No. 166,104.

My invention relates to an attachment or auxiliary device for radio receiving sets and the object is to provide a simple, highly efficient device which eliminates the use of an antenna with any set; a further object being to provide for positive selection of reception according to wave lengths, said wave lengths commonly designated by meters. One result in the use of my device is greatly increased clearness and volume of tone in the receiving set.

In the accompanying drawing:

Fig. 1 is a partly sectional top view of a horizontal type of my device adapted for mounting in a radio panel.

Fig. 2 is a sectional detail as on line 2—2 of Fig. 1.

Fig. 3 is an enlarged sectional detail as on line 3—3 in Fig. 2 showing mounting of a preferred type of contact clips used in my coil construction.

Fig. 4 is a top view and Fig. 5 a partly sectional side elevation of a vertical type of my device.

Fig. 6 is a circuit diagram of my coil and adjacent parts of a receiving set including the first stage in the power tube of said set.

Referring to the drawing by reference numerals, 10 is the vertical front panel of a radio receiving cabinet the part of it shown being in proximity to the usual dials of the radio set (not shown). Referring particularly to Figs. 1 and 2, 11 is an aperture in panel 10 through which the center bearing 12^B of a web casting 12 projects forwardly and its outer part threaded for nuts 13, said web having a circular flange 12^F which retains and centers the front end of an elongated cylinder 14. The rear end of said cylinder 14 is closed by a removable cap 15 bored centrally for a removably fixed, threaded rod 16 the rear exposed end of which is adapted to receive the jam nuts 17; the front end of said rod projecting forward of the bore of web 12 and having a head 16^H. On said head is suitably fixed as at 19 a rotary dial 18 with a manipulating button 20.

14^R are a number of longitudinal, integral, parallel ribs of cylinder 14 on the inner side of the latter. Said ribs constitute guides for an insulated crosshead 21 having

a central threaded collar 22 engaging the threaded rod 16, said collar 22 fixed in said crosshead by means of jam nuts 22^A and 55 adapted to move the latter according to rotation of dial 18.

23 are close wound coils of a single insulated wire wound on the cylinder 14 throughout its length, the front end of said wire fixed to the grounded side of the radio set as at 14^A (see also Fig. 6) and the rear end fixed to a contact 25 and thence preferably extending as 14^B to the antenna side of the receiving set (Fig. 6). For each rib 14^R the crosshead 21 is provided with a radial bore 26 having an electroconductive ball 27 and a coiled pressure spring 28 back of it normally pressing the ball against the top of a rib 14^R. 29 are a series of contact clips 70 each with a head portion 29^H exposed inwardly of rib 14^R and having a double shank extended outwardly through the wall of cylinder 14 and the ends of said shank being forked (as at 29^A in Fig. 3) to frictionally receive and retain the wire 23 which is not insulated at these points. 29^B indicates the forked ends closed about the wire. It will be understood that these wire retaining clip ends are arranged close together in each rib 75 and all the ribs but the wire is tapped by a clip only for each one and a quarter turn or winding (four hundred and fifty degrees apart). When moving the crosshead by means of rotating the dial 18 it is obvious 80 that only one ball at a time establishes a lead in contact from the coils through the ball 27 the spring 28 and thence through sleeve 22, the latter in turn transmitting current through screw rod 16 thence to plate 90 12, through an outer lateral flange 12^F of said plate, through a contact 30 grounding current at 32 through wire 31 (see Figs. 1 and 6). The size of coil and winding are such that each contact 29 being spaced one 95 and a quarter revolution from the next contact corresponds to one meter of wave length as computed for radio broadcasting purposes. The crosshead starts movement from a position near the front panel at which time the adjacent receiving set is tuned in for receiving a broadcasting program of low wave lengths.

Moving the crosshead rearwardly estab-

lishes circuit as described through an increasing number of windings and which windings corresponds to the number of meters in the wave lengths of various broadcasting stations.

In Fig. 6 the coils 33^P is the primary winding and 33^S the secondary winding represent a radio transformer. 34 is a resistance connected at 35 to a power or vacuum tube 36 of a radio receiving set.

In the modified form shown in Figs. 4 and 5 the device is mounted vertically the rod 16 being vertically mounted but has no head as 16^H, the upper end being plain and retained within a bell-shaped rotatable shell 37 by means of a pin 38. The lower rim of shell 37 has suitable degree markings 37^M which correspond to the metric wave lengths of various broadcasting stations. These markings will pass a suitable stationary marker 40 on an insulated base 39. The said base has an integral central bearing or pocket 39 within which the nuts 17 engage rod 16. 30^X is a contact screw corresponding to screw 30 in Fig. 1 and through said screw circuit is grounded as through the wire 31 in Fig. 1. This form of the device serves two desirable purposes namely to shield the coil and provide an independent attachment applicable to any receiving set, where-

as the form shown in Figs. 1 and 2 are built-in units of a radio receiving set.

I claim:

In a radio receiving set, a tuning coil comprising a rotatably mounted dial, a threaded shaft fixed to and concentric of said dial, a cylinder fixed concentrically about said shaft, an insulated wire wound in close coils on the exterior face of said cylinder, parts of said wire exposed at predetermined spacings throughout its length, a number of longitudinally arranged circularly spaced ribs on the interior of said cylinder, said wire attachable at one end of an antenna wire, a crosshead threaded at its center to engage and be moved on the threaded shaft, guide means on said crosshead engaging said ribs, electro conductive communicating means between said exposed wire parts within said ribs and adapted to be engaged progressively by the crosshead according to the movement of the latter by the rotation of the dial, an electro conductive web in the end of said cylinder nearest the dial and the other end of said wire connected therewith and means for connecting said web with a ground wire.

In testimony whereof I affix my signature.

PETER MERTES, JR.
